INVENTOR,

Milton B. Kirker.
by George H. Christy Atty.

UNITED STATES PATENT OFFICE.

MILTON B. KIRKER, OF PITTSBURG, PENNSYLVANIA.

WHIFFLETREE-COUPING.

SPECIFICATION forming part of Letters Patent No. 372,681, dated November 8, 1887.

Application filed February 19, 1886. Serial No. 192,529. (No model.)

To all whom it may concern:

Be it known that I, MILTON B. KIRKER, residing at Pittsburg, in the county of Allegheny and State of Pennsylvania, a citizen of the United States, have invented or discovered certain new and useful Improvements in Doubletrees and Fittings Therefor, of which improvements the following is a specification.

In the accompanying drawings, which make part of this specification, Figure 1 is a rear elevation of my improved construction of doubletree and fittings. Figs. 2, 3, and 4 are sectional views on the lines $x-x$, $y-y$, and $z-z$, Fig. 1, respectively, showing two forms of construction of the devices for connecting the singletrees to the ends of the doubletree. Fig. 5 is an elevation of a neck-yoke.

The invention herein relates to certain improvements in the construction and arrangement of clips for uniting whiffletrees to doubletrees, whereby a strong and durable connection for said parts is obtained; and to this end my invention consists in the construction and combination of parts, substantially as hereinafter more fully described and claimed.

The whiffletrees 1 and the doubletree 2 are formed of wrought-iron or steel tubes tapering slightly from the middle to the ends, as clearly shown. To the ends of the whiffletrees are secured the usual fittings, 3, for the attachment of the traces. These fittings 3 are formed of malleable cast-iron, and the cylindrical portion adapted to fit over the ends of the whiffletrees is formed with an internal diameter 35 slightly less than the external diameter of the tubes 1 at their ends. In attaching the connections to the tubes said connections are expanded by heat and then slipped onto the ends of the tubes. The contraction of the 40 metal of the connections will firmly secure them to the ends of the tubes, thus avoiding the necessity of bolts or rivets.

In connecting the tubes 1 to the tube 2, to form a doubletree, I use a clip or connection 45 composed of two cylindrical blocks, 4 and 5, formed of malleable cast-iron, having longitudinal openings therethrough for the reception of the tubes 1 and 2, to which said blocks are secured by shrinking on in the manner 50 above described. On the lower side of the block 4 is formed a boss or projection, 6, hav-

ing a circular recess for the reception of a correspondingly-shaped projection, 7, formed on the upper side of block 5, said projection forming a pivot for the block 4 on the whiffletree 1. These blocks are held together by the transverse bolt 8, as shown. The upper side of the block 4 and the under side of the block 5 are flattened to form a bearing for the ends of the brace 9, through which the ends of the 60 bolt pass. This brace, which serves to support the upper end of the bolt as against transverse strains, may be and preferably is formed integral with the block 5, as shown in Fig. 2.

The connection 10 for attaching the doubletree to the wagon is shrunk on the tube in the manner above described, and consists of the ring portion 11, the handle or lifting-bail 12, the draft-ring 13, and the fastening arm or lug 14. This connection or fitting, as are all 70 the fittings, is formed of malleable iron. The fitting 3 consists of the cylindrical portion adapted to fit over the ends of the singletrees and the ring to which the traces are connected.

The single and double trees may be formed 75 of any suitable metal, as desired.

The above-described improvement in connecting fittings of malleable cast-iron to single and double trees is equally applicable for connecting the malleable cast-iron fittings 15 80 to tubular metal neck-yokes 16, as will be readily understood.

No claim is made herein to the manner of securing the fittings onto the double-trees, as such construction or method of securing the fittings 85 in place forms the subject-matter of another application, filed February 24, 1887.

I claim herein as my invention—

1. The combination of a metal tubular doubletree and singletrees with a malleable-iron 90 central fitting therefor, consisting of the ring 11 and the bail 12, substantially as set forth.

2. The combination of a metal tubular doubletree and singletree with a malleable-iron central fitting therefor, consisting of the ring 95 11, the bail 12, and the draft-ring 13, substantially as set forth.

3. As an article of manufacture, the herein-described fitting for doubletrees, consisting of the ring 11, the bail 12, the draft-ring 13, and 100 the fastening-lug 14, substantially as set forth.

4. In a clip for connecting singletrees and

doubletrees together, the combination of the cylindrical portion 4, having a recessed projection, 6, the cylindrical portion 5, having the projection 7, the bolt 8, and a brace, 9, for laterally supporting said bolt, substantially as set forth.

5. In a clip for connecting singletrees and doubletrees together, the combination of the cylindrical portion 4, having the recessed projection 6, the cylindrical portion 5, having the

projection 7, the bolt 8, and the brace 9, formed integral with the portion 5, substantially as set forth.

In testimony whereof I have hereunto set my hand.

MILTON B. KIRKER.
